FRED. W. BURROWS, OF NEW YORK, N. Y.

Design No. 3,214, dated November 3, 1868.

DESIGN FOR A TOBACCO-PIPE.

The Schedule referred to in these Letters Patent and making part of the same.

To all whom it may concern:

Be it known that I, FRED. W. BURROWS, of the city, county, and State of New York, have invented a new and original Design for Cigar and Tobacco-Pipe; and I do hereby declare that the following is a full, clear, and exact description thereof, which will enable others skilled in the art to make and use the same, reference being had to the accompanying drawing, forming part of this specification.

The drawing represents a side view of a pipe formed according to my design.

The design consists in forming the bowl A to resemble a ball, such as generally used in playing the

game of base-ball, and forming the tube or stem B of the pipe to resemble the bat used in the same game.

Having thus described my invention,

I claim as new, and desire to secure by Letters Patent—

The design for a cigar and tobacco-pipe, consisting of a ball, A, and bat B, as shown and described.

The above specification of my invention signed by me, this 29th day of September, 1868.

FRED. W. BURROWS.
